US00D614592S

(12) **United States Design Patent**
Hussell et al.

(10) **Patent No.:** **US D614,592 S**
(45) **Date of Patent:** **** Apr. 27, 2010**

(54) **LIGHT EMITTING DIODE**

(75) Inventors: **Christopher P. Hussell**, Cary, NC (US);
Shuying Huang, Apex, NC (US)

(73) Assignee: **Cree, Inc.**, Durham, NC (US)

(**) Term: **14 Years**

(21) Appl. No.: **29/342,451**

(22) Filed: **Aug. 25, 2009**

Related U.S. Application Data

(62) Division of application No. 29/323,659, filed on Aug. 28, 2008, now abandoned.

(51) **LOC (9) Cl.** **13-03**

(52) **U.S. Cl.** **D13/180**

(58) **Field of Classification Search** D13/180;
D26/2; 257/79, 80, 81, 88, 89, 95, 98, 99,
257/100; 313/483, 498, 500; 362/555, 800

See application file for complete search history.

(57) **CLAIM**

The ornamental design for a light emitting diode, as shown and described.

DESCRIPTION

FIG. 1 is a front perspective view of an embodiment of an LED showing my design;

FIG. 2 is a front view thereof;

FIG. 3 is a bottom view thereof;

FIG. 4 is an opposing top view thereof;

FIG. 5 is a back view thereof opposite the view of FIG. 2

FIG. 6 is a side view thereof;

FIG. 7 is an opposing side view thereof; and,

FIG. 8 is a back perspective view thereof.

The broken lines shown herein are for illustrative purposes only and form no part of the claimed design.
